UNITED STATES PATENT OFFICE.

NORMAN M. JOHNSTON, OF FREMONT, OHIO.

CAPO TASTO.

Application filed May 11, 1925. Serial No. 29,443.

This invention relates to devices for raising the pitch of stringed instruments, and especially fretted instruments such as guitars, banjos and ukeleles.

5 The objects of the invention are to provide a permanent attachment upon the head or neck of the musical instrument, a capo tasto being adjustably carried by said attachment and arranged to be normally held in an inoperative position and to be quickly adjusted to stop the strings adjacent to any desired fret in order to raise the pitch of the instrument accordingly; the device being so constructed that it will at no time interfere with the free 10 movement of the hands in playing the instrument.

The above and other objects are attained by providing a table permanently attached to the head, or outer end of the neck, of a 20 stringed instrument, a slotted bar being longitudinally adjustable thereon by means of a clamping screw and having a cross head at its inner end arranged to be clamped across all of the strings.

25 An embodiment of the invention is illustrated in the accompanying drawing, in which—

Figure 1 is a side elevation of the neck portion of a musical instrument, showing 30 the improved capo tasto attachment thereon; and

Fig. 2, a plan view of the same.

Similar numerals of reference indicate 35 corresponding parts throughout the drawing.

The neck of a stringed musical instrument is shown at 1, provided with the head 2, which is usually inclined downward therefrom, at an angle, as shown in Fig. 1.

40 The strings 3 are shown stretched, in the usual manner, between the tail piece (not shown) and the pegs 4 in the head, and normally held slightly spaced above the frets 5 by the nut 6, all of said construction being 45 usual and well known in instruments of this general class.

The present improvements includes the table 7, substantially parallel with the plane of the neck 1, and preferably provided, near its inner end, with the angular, inverted U-shaped portion 8, in which is housed a nut 9, for engagement with the clamping screw 10.

50 Feet 11, are formed at the ends of this table for permanently attaching the same

to the head of the instrument, as by the screws 12.

The capo tasto element comprises a metal bar 13, slotted longitudinally as at 14, to receive the clamping screw 10, and arranged 60 to be slidably mounted upon the top of the U-shaped portion 8, a downturned outer end 14', of the bar, engaging the top of the table and holding the bar substantially parallel therewith when the clamping screw is 65 tightened.

A cross head 15 is formed at the inner end of the bar 13, which may be curved slightly downward as shown at 16, a bar 17 of wood, fiber or the like, being fixed to the under 70 side of the cross head for engagement with the strings, as shown in the drawing.

By sliding the bar 13 longitudinally until the cross head is located adjacent to the fret at which it is desired to stop the strings, the 75 clamping screw is tightened clamping the cross bar 17 tightly upon all of the strings and holding the strings against the top of the adjacent fret, as shown at A, in Fig. 1.

The downturned outer end 14', of the bar 80 13, being in contact with the table, prevents any tilting of the bar 13, thus assisting the clamping screw in holding the cross bar tightly upon the strings.

When the capo tasto is not in use, the bar 85 13 is slidably moved outward until the cross bar 17 is beyond the nut 6, and the clamping screw is tightened, holding the attachment in this position.

I claim:

1. A capo tasto attachment for a stringed instrument having a head, comprising a table 90 permanently attached to the head, a bar slidably mounted upon the table and having an inturned outer end engaging the table and a 95 cross head, for engagement with the strings of the instrument and a clamping screw associated with the table for clamping the bar in adjusted position.

2. A capo tasto attachment for a stringed 100 instrument having a head, comprising a table permanently attached to the head, a nut carried by the table, a bar slidably mounted over the nut and having an inturned outer 105 end engaging the table and a cross head at its inner end for engagement with the strings, and a clamping screw associated with the nut for clamping the bar in adjusted position.

3. A capo tasto attachment for a stringed 110

2

instrument having a head, comprising a table permanently attached to the head and having an inverted U-shaped portion near its inner end, a nut located in said U-shaped portion, 5 a bar slidably mounted upon said U-shaped portion and having an inturned outer end engaging the table, a cross head at the inner end of the bar for engagement with the strings, and a clamping screw associated 10 with the nut for clamping the bar in adjusted position.

4. A capo tasto attachment for a stringed instrument having a head, comprising a table permanently attached to the head, a bar 15 slidably mounted upon the table and having an outer end engaging the table and a cross head for engagement with the strings of the

instrument, and clamping means associated with the table for clamping the bar in adjusted position.

5. A capo tasto attachment for a stringed instrument having a head provided with a table portion, a slotted bar slidably mounted upon the table and having an inturned outer end engaging the table and a cross head for engagement with the strings of the instrument, and a clamping screw associated with the head and extended through the slot in the bar for clamping the bar in adjusted 20 position.

25 In testimony that I claim the above, I have hereunto subscribed my name.

30 NORMAN M. JOHNSTON.
